CLAIM

The ornamental design for a therapeutic vaporizer insert, as shown and described.

DESCRIPTION

FIG. 1 is a top left perspective view of a therapeutic vaporizer insert;

FIG. 2 is a top view of the therapeutic vaporizer insert of FIG. 1;

FIG. 3 is a bottom view of the therapeutic vaporizer insert of FIG. 1;

FIG. 4 is a front view of the therapeutic vaporizer insert of FIG. 1;

FIG. 5 is a rear view of the therapeutic vaporizer insert of FIG. 1;

FIG. 6 is a left side view of the therapeutic vaporizer insert of FIG. 1; and,

FIG. 7 is a right side view of the therapeutic vaporizer insert of FIG. 1.

The broken lines in the drawings depict portions of the therapeutic vaporizer insert that form no part of the claimed design.

1 Claim, 7 Drawing Sheets
